SNAP FASTENER CARDING MACHINE

Max Kiessling, Waterbury, Conn., assignor to
 The American Fastener Company, Waterbury,
 Conn., a corporation of Connecticut

Application February 5, 1948, Serial No. 6,464

15 Claims. (Cl. 218—18)

1
 This invention relates to machines for applying snap fasteners to cards, and more particularly to a machine for automatically assembling male and female snap fastener sections with the cards upon which the fasteners are to be displayed and sold.

This machine is constructed for use with fasteners of the type having two complementary sections, each of which has the shape of a disk with a central projection, the projection of one section being adapted to snap within the projection of the other section, wherein it will be held by the resilient action of the latter.

It is customary to apply snap fasteners to perforated display cards by assembling or closing the respective fastener sections in such a manner that the card is confined between them. Heretofore this operation has been done by hand, with the result that it was slow, tedious, and so expensive that it represented a substantial part of the cost of the product.

Accordingly, one object of this invention is to provide a machine of the above nature which includes mechanism for automatically applying a predetermined number of snap fasteners to each display card.

Another object is to provide a device of the above nature which includes means for closing a succession of the snap fasteners at a fixed location in the machine, and means for rotating the display card so that a circular series of fasteners will be applied thereto.

Another object is to provide a device of the above nature having means for automatically stopping the machine and releasing the display card after the card has received the predetermined number of fasteners.

A further object is to provide a machine of the above nature which will be relatively simple in construction, inexpensive to manufacture, easy to install and manipulate, compact, and very efficient and durable in use.

With these and other objects in view, there has been illustrated on the accompanying drawing one form in which the invention may conveniently be embodied in practice.

The male fastener sections will be referred to hereinafter as studs, and the female fastener sections will be referred to as springs—these being the terms commonly used in the trade.

In the drawings,
 Fig. 1 is a top plan view of the machine.
 Fig. 2 is a front elevation of the same.
 Fig. 3 is an end view of the machine looking from the left in Figs. 1 and 2.

2
 Fig. 4 is a cross sectional view on the line 4—4 of Fig. 1, looking in the direction of the arrows, with the display card shown in broken lines.

Fig. 5 is a cross sectional view, on the broken line 5—5 of Fig. 1.

Fig. 6 is a cross sectional view, on the line 6—6 of Fig. 1, showing the spring feed and the spring slide, the latter being in withdrawn position.

Fig. 7 is a cross sectional view on the broken line 7—7 of Fig. 1, behind the card, showing the stud escape and feed, the feed slide being in withdrawn position.

Fig. 8 is a cross sectional view on an enlarged scale, on the line 8—8 of Fig. 1, showing the snap fastener closing mechanisms, the card holder, a card therein, and a stud and a spring at opposite sides thereof.

Fig. 9 is a cross sectional view, showing a portion of Fig. 6 on an enlarged scale, the spring feed slide being in its advanced position.

Fig. 10 is a cross sectional view, showing a portion of Fig. 7 on an enlarged scale, but showing the stud feed slide in its advanced position, and the escape member in open position.

Fig. 11 is a cross sectional view, on an enlarged scale, taken on a portion of the line 8—8 of Fig. 1, with the stud and spring members in position ready to be closed upon the card.

Fig. 12 is a view similar to Fig. 11, but showing the stud and spring members assembled upon the card.

Fig. 13 is a plan view of a rectangular display card upon which a pair of snap fasteners have been attached.

Fig. 14 is a fragmentary cross sectional view similar to Figs. 11 and 12, taken along the line 8—8 of Fig. 1, with the stud and spring carriers in a partially retracted position, ready to permit removal of the display card.

Fig. 15 is a horizontal cross-sectional view, on an enlarged scale, looking downwardly on the line 15—15 of Fig. 6, showing both stud and spring carriers in fully retracted position.

Fig. 16 is a cross-sectional view, on an enlarged scale, taken on the line 16—16 of Fig. 7, showing the stud escape mechanism in open position.

Fig. 17 is a cross-sectional view taken on the line 17—17 of Fig. 10, showing the stud escape mechanism in closed position.

Fig. 18 is a cross-sectional view, similar to Fig. 15, taken on the line 18—18 of Figs. 9 and 10, but showing the stud and spring carriers at the instant of engaging a stud and a spring advanced by the stud feed slide and the spring feed slide.

Fig. 19 is a detail view of a portion of Fig. 9,

showing the spring feed slide and magazine, but with the spring slide in a partly withdrawn position.

Fig. 20 is a detail view of the stud magazine and feed mechanism, similar to Figs. 7 and 10, but showing the stud feed slide in a partly withdrawn position.

Fig. 21 is a cross-sectional view on the line 21—21 of Fig. 19, showing the appearance of a spring located on the spring carrier preparatory to the final closing movement.

Fig. 22 is a sectional view, substantially on the line 22—22 of Fig. 20, showing the appearance of a stud located on the stud carrier, preparatory to the final closing movement.

Referring now to the drawings in which like reference numerals denote corresponding parts throughout the several views, the numeral 10 indicates a rectangular machine bed having a left hand rectangular pedestal base 11, and a right hand rectangular pedestal base 12, secured in spaced relation upon the front portion of said bed by means of bolts 13. The left hand pedestal base 11 is provided with a pair of spaced upstanding pedestals 14, 15, and the pedestal base 12 is provided with a pair of spaced upstanding pedestals 16, 17, all of said pedestals being disposed in alignment across the front portion of the bed 10.

The pedestals 14, 15 are provided with aligned horizontal bearings 18, 19 (Fig. 2) rotatably supporting a card holder shaft 20, and the pedestals 16, 17 are provided with aligned bearings 21, 22 rotatably supporting a clamping plate shaft 23, whereby said shafts 20 and 23 are supported in coaxial relation with their inner ends disposed in the space between the pedestals 15, 16.

Card holder

A card holder 24 is secured on the inner end of the shaft 20 by means of a central hub 25 on the back of the holder, and a set screw 26 in said hub. The card holder 24 is adapted to support a display card C (Fig. 13), in a vertical plane between the pedestals 15, 16, in such a manner that a circular series of perforations P in the card C will be held in coaxial relation with the card holder shaft 20. In order to hold the card C accurately in position, the holder 24 has a flat face 27, side walls 28 and 29 adapted to confine the side edges of the card C, and an end wall 30 (Fig. 6) which holds an adjustable abutment 31 for locating one end of the card C.

The display card C will be clamped against the flat face 27 of the card holder 24 by means of a flat clamping plate 32 secured on the inner end of the clamping plate shaft 23 by means of a central hub 33 upon its rear face, and a set screw 34 in said hub.

The clamping plate shaft 23 and the clamping plate 32 thereon are adapted to have limited longitudinal movement in order to clamp or release the card C within the holder 24. Means to be described hereinafter is provided for accomplishing this movement.

The card holder 24 and the clamping plate 32 are each provided with a circular series of apertures 35, 36, respectively, which are best seen in Figs. 6 and 8. These apertures 35, 36 will be disposed in alignment with the perforations P of a card in the holder 24, and will be brought successively into alignment with a stud carrier 37 and a spring carrier 38, as the card holder 24 is rotated, so as to permit application of studs D and springs S to said perforations.

It will be seen by reference to Figs. 13 and 14 that the studs D and the springs S will be snapped together or "closed" from opposite sides of the card C to form complete fasteners F, the stud D of each fastener being disposed in one of the perforations P.

A step-by-step rotating motion is imparted to the card holder 24 by means of a ratchet wheel 39 secured upon the outer end of the card holder shaft 20 and having teeth 40 equal in number to the perforations P in the card C.

Thus, as the card is rotated in the holder 24, each of the perforations P will be brought in turn to a position between the stud carrier 37 and the spring carrier 38, whereby the fasteners may be applied to the respective perforations.

The machine bed 10 is provided with a slot 41 in order to provide clearance for rotation of the card holder 24.

In order to drive the ratchet wheel 39 and other mechanisms of the machine, provision is made of a main drive shaft 42 mounted in a lateral position upon the rear portion of the bed 10 by means of flanged bearing blocks 43, 44 secured by bolts 45, 46. The drive shaft 42 is retained in the bearing blocks 43, 44, by means of bearing caps 47, 48 which are secured by bolts 49.

A driving connection between the drive shaft 42 and the ratchet wheel 39 is established by means of a crank 50 on the shaft 42, a connecting rod 51 secured to the crank, a lever 52 swingably carried upon the card holder shaft 20 outwardly of the ratchet wheel 39, and a pawl 53 which engages the teeth 40 of the ratchet wheel. Thus, rotation of the drive shaft will cause the ratchet wheel to be advanced intermittently.

In order to prevent the card holder 24 from turning too far at the end of each advancing movement, a pair of friction members 54, 55 engage the shaft 20 between the pedestals 14, 15. A clamping screw 56 is provided whereby the friction members 54, 55 may be adjusted to exert the desired braking action upon the shaft 20. The friction members 54, 55 are held in place by means of a flange 57 which is formed on the member 54 and secured to the upper surface of the pedestal base 11 by means of a bolt 58.

Thus, the rotation of the card holder 24 will be accurately controlled so that the perforations P of the card C in the holder 24 will be stopped exactly in line with the stud carrier 37 and the spring carrier 38.

Driving and clutch mechanism

The main drive shaft 42 will be rotated continuously during the application of the snap fasteners F to a card, so that the fasteners will be applied successively until the card C has made one complete revolution and all of the perforations P therein have received fasteners. The drive shaft 42 will then be automatically stopped.

This feature of the operation is accomplished by means, best seen in Figs. 1, 2 and 4, which includes a fly wheel 59 loosely retained upon the right-hand end of the drive shaft 42 by means of a collar 60, and engaged by a belt 61 which is constantly driven by any suitable source of power. A releasable driving connection is provided between the fly wheel 59 and the drive shaft 42 in the form of a clutch indicated generally as 62. The clutch 62 comprises a cylindrical body 63 having an inner longitudinal aperture 64 which carries a bolt 65 adapted to engage a slot 66 in the hub of the fly wheel 59.

The bolt 65 is normally spring pressed into engagement with the slot 66, but is provided with a head 67 which is engageable by a clutch arm 68, whereby it may be withdrawn from said slot 66.

The clutch arm 68 is carried on a bracket 69 at the rear of the bed by means of a pivot pin 70, and is provided with a curved front end portion 71 which conforms to the curvature of a reduced section 72 of the clutch body 63. The arm 68 is normally urged upwardly against the reduced section 72 by means of a coiled spring 73, whereby an inclined cam surface 74 on the end portion 71 of the clutch arm 68 will engage behind the bolt head 67 as it rotates with the body 63, to withdraw the bolt 65 from the slot 66. A lateral stepped abutment 75 is also provided on the arm 68, which is adapted to engage the head 67 of the bolt 65 during rotation of the shaft 42 in order to bring said shaft to a positive stop.

In order to release the bolt 65 so as to reengage the clutch, provision is made of a clutch trip rod 76 (Figs. 2 and 4) which is connected to a central portion of the clutch arm 68 by means of a pin 77 and is vertically slideable in a guide 78 on the machine bed 10. A link 79 is provided for connecting the clutch trip rod 76 to any suitable actuating means, so that the trip rod 76 may be moved downwardly to swing the clutch arm 68 and thereby permit the bolt 65 to enter the slot 66 and start the machine, whenever desired by the operator.

Tripping of the rod 76 will initiate a machine cycle during which the drive shaft 42 will make a predetermined number of revolutions, whereupon the clutch will automatically be thrown out of engagement.

In order to accomplish this, provision is made of means including a cam 80 which is secured to the main drive shaft 42 inwardly of the bearing block 44, and adapted to depress a lever 81 once in each revolution of the shaft 42 by means of a cam follower 82 on said lever. The lever 81 is pivotally mounted in a block 83 secured to the rear edge of the bed 10, and is connected at its front end to a coiled spring 84 supported by a bracket 85 held under the head of one of the bearing cap bolts 49, so that the follower 82 will be maintained against the peripheral surface of the cam 80.

The lever 81 is operatively connected to a ratchet wheel 86, which is secured upon the inner end of a horizontal control shaft 87 in a bearing block 88 on the bed 10, by means of a link 89, a ratchet lever 90, and a pawl 91. The teeth of the ratchet wheel 86 are equal in number to the teeth of the ratchet wheel 39 on the card holder shaft 20, and to the number of perforations P in the display card C.

The outer end of the control shaft 87 is provided with a control disk 92 (Figs. 1, 3 and 4) having a cam projection 93 on its inner face for a purpose to be described hereinafter. The outer face of the control disk 92 has an eccentric clutch release pin 94 adapted to engage a cam nose 95 on the forward end of a clutch release lever 96, which is pivoted on the side of the machine bed 10 by means of a stud 97. The release lever 96 has a tapered rear end 98 which is adapted to engage in a notch 99 in the clutch trip rod 76 so as to hold said rod in a depressed position. However, it will be seen that when the ratchet wheel 86 (and concurrently, the card C) has made one complete revolution, the re-

lease pin 94 will strike the cam nose 95, whereby the rear end 98 of the release lever 96 will be disengaged from the trip rod 76 to permit the clutch arm 68 to swing upwardly and thereby disengage the clutch and stop the machine. The rear end 98 of the lever 96 will be urged against the trip rod 76 by means of a coiled spring 100 connected to the release lever 96, so that tripping of the rod 76 will cause the end 98 to engage in the notch 99 and thereby maintain the machine in operation until the release lever 96 is engaged by the release pin 94.

Card clamping mechanism

In order to release the clamping plate 32 from a card C in the holder 24 at the end of one revolution of the card, provision is made of means including a cam piece 101 which is secured to the side of the cam 80. The cam piece 101 is engageable with a follower 102 upon the rear arm of a bell-crank release lever 103 which is swingably mounted under the head of the bearing block mounting bolt 46. The forward arm of the bell-crank lever 102 has a depending pin 104 engageable with the rear end of an offset lever 105. The offset lever 105 is pivoted on a stud 106 upstanding on the pedestal base 12, and is provided adjacent the pin 104 with an inclined end surface 107 having a rounded recess 108 at its high point. The inclined end surface 107 and the recess 108 are engaged by a slideable detent 109 which is carried in a tubular guide 110 upon the control shaft bearing block 88 and pressed outwardly by a coiled spring 111 so as to maintain the rear arm of the offset lever 105 selectively in different positions.

The other end of the offset lever 105 is in the form of a yoke 112 engaged in an annular groove 113 in the outer end of the clamping plate shaft 23. The offset lever 105 will normally be urged in a clockwise direction by a coil spring 114, so that the clamping plate shaft 23 and the clamping plate 32 thereon will clamp the card C firmly in the card holder 24.

However, provision is made of a nose 115 so disposed upon the outer side of the rear arm of the offset lever 105 that it will lie in the path of the cam projection 93 of the control disk 92 when the clamping plate 32 is in its clamping position. Thus, when the card C, and consequently, the disk 92 have made one complete revolution, the cam projection 93 will engage the nose 115 to move the offset lever 105 in a counterclockwise direction, whereupon the detent 109 will engage in the recess 108 to hold the clamping plate 32 in its released position as seen in Figs. 1, 2, and 8.

The parts will remain in this position until the machine is again started by the operator, whereupon the cam piece 101 will actuate the bell-crank release lever 103 to release the offset lever 105 from the detent 109, so that the plate 32 will again clamp a card in the card holder 24.

It will be noted that the release lever 103 will be in an inactive condition excepting during the first revolution of the drive shaft 42 which occurs after the rod 76 is tripped.

Stud and spring feed

In order to supply the snap fastener studs D and springs S to the machine, provision is made of a vertical stud magazine 116 and a vertical spring magazine 117, which are best seen in Figs. 1, 2, and 9.

The stud and spring magazines 116, 117, comprise, respectively, chute members 118 and 119

having guide channels 120, 121 and pairs of retaining strips 122, 123 secured by screws 124 in longitudinal positions overhanging the channels 120, 121.

In order to support the magazines 116, 117 and other related mechanisms, mounting blocks 125, 126 are secured to the upper inner corner portions of the pedestal 15, and a pair of mounting blocks 127, 128 are secured upon the upper inner corner portions of the pedestal 16 (Figs. 2, 9, 10, 10 and 18).

The blocks 125, 126, 127, 128 are formed with notches 129 in their lower inner corners (Fig. 18) so that the blocks will seat firmly upon the pedestals and are secured thereon by means of screws 130 (Fig. 2). The stud and spring magazines 116, 117 are secured respectively in a recess 131 in the mounting block 1255 (Fig. 10), and in a recess 132 in the mounting block 128 (Figs. 8 and 9), by means of screws 133, 134, so as to be flush with the inner faces of the mounting blocks.

The lower end of the stud magazine 116 is seated upon the upper surface of a stud feed indicated generally as 135, which is secured in slots 136, 137 in the outer faces of the mounting blocks 125, 126 (Figs. 10, 11, 12).

The stud feed 135 comprises a bar 138 (Figs. 10, 11, 18) having a horizontal stud channel 139 in its front face, and an entrance slot 140 (Fig. 10) which is aligned with the channel 120 of the stud magazine so as to permit passage of the studs downwardly from the magazine 116 into the stud channel 139.

The stud channel 139 contains a feed slide 141 extending inwardly from its front end, said slide having a notched rear end 142 comprising an extended lower lip 143. The lower lip 143 and the upper edge portion 144 of the slide are of reduced thickness so as to accommodate the disk portions of the studs D. The rearward portion of the stud channel 139 is provided with an abutment 145 for the disk portions of the studs, so as to limit rearward movement of the studs in the channel.

The stud feed 135 is provided with a cover plate 146 adjacent the card holder 24 having a channeled rearward portion 147 to permit the operation of a stud stripper 148, to be further described hereinafter.

The feed slide 141 is reciprocated by means of an operating slide 149 which is disposed in a channel 150 upon the rear face of the bar 138, and connected to the front end of the feed slide 141 by means of a screw 151 and a filler piece 152. The operating slide 149 is operated from the main drive shaft 42 by means of a cam 153 on said shaft 42 (Figs. 7 and 10). A follower 154 is held against the periphery of the cam 153 by an arm 155, which is swingably carried in a block 156 on the machine bed 10 and urged rearwardly by means of a spring 157 held by a rod 158 which is supported at the rear edge of the bed 10. The arm 155 is connected to the operating slide 149 by means of a link 159 and a pivot pin 160 (Figs. 7, 10, and 15).

In order to release the studs D from the magazine 116 one at a time, so as to be picked up by the stud feed slide 141, provision is made of an escape mechanism 161 shown in Figs. 7, 16, 17, and 20, which comprises a horizontal operating slide 162 retained against the back of the chute member 118 of the magazine 116 by means of a slotted guide 163 and screws 164. The operating slide 162 has enlarged ends 165, 166 to which a stud retaining slide 167 and a stud escape slide 168 are attached, in positions directed toward

each other, by means of screws 169. The slides 167, 168 are slideable across the face of the chute member 118 in channels in the backs of the retaining strips 122.

The retaining slide 167 has a rearwardly-inclined end surface 170 (Figs. 10 and 20) and the inner end of the escape slide 168 has a finger 171 of reduced width, thereby forming a slot 172 which will permit the downward escape of one stud D in the channel 120 at each reciprocating movement of the slides 167, 168.

Provision is made of a pair of projecting pins 173, 174 upon the enlarged forward end 165 of the operating slide 162 and upon the guide 163, respectively, for mounting a coiled spring 175 whereby the escape mechanism will be urged rearwardly (to the right in Fig. 16).

In order to slide the escape mechanism forwardly so as to release the studs D at the desired intervals, provision is made of a link 176 pivotally connecting the rear end of the escape operating slide 162 with the upper end of an escape lever 177 swingably mounted upon a bracket 178 on the mounting block 126. The escape lever 177 has a lower end 179 which depends in the path of an abutment roller 180 carried by the pivot pin 160 of the stud feed operating slide 149 (Fig. 10). Thus, the link 159 of the stud feed operating mechanism will serve to operate both the stud feed and the stud escape mechanisms.

The lower end of the spring magazine 117 is seated upon the upper surface of a spring feed 181 (Figs. 9, 11, 18) which is secured in slots 182 and 183 in the outer faces of the mounting blocks 127, 128, respectively. The spring feed 181 comprises an inner cover plate 184 and a bar 185 formed with a horizontal spring channel 186 in its inner face, and a vertical entrance slot 187 (Figs. 9, 19) in alignment with the guide channel 121 of the spring magazine 117, whereby the springs may be fed from the magazine into the spring channel 186.

A spring feed slide 188 is guided in the channel 186 and is provided with a stepped forward end 189 which serves as a backing flange for the springs S. The forward end of the spring channel 186 is provided with a filler block 190, which serves as an abutment to limit the forward movement of the springs S, as they are fed forwardly one-by-one by the spring feed slide 188.

The spring feed 181 is provided with an outer cover plate 190a which is channelled on its inner face to permit the operation of a spring stripper 190b to be further described hereinafter.

The spring feed slide 188 is operated from the main drive shaft 42 by means of a cam 191 (Figs. 1 and 6). A follower 192 is mounted upon a bell-crank lever 193 swingably carried on a block 194 on the bed 10, and is held against the cam 191 by means of a spring 195 (Figs. 1 and 6), which is carried upon a bracket 196 upon the machine bed 10, and connected to an ear 197 on the end of the lower arm of the bell-crank lever 193. The spring feed slide 188 and the upper arm of the bell crank lever 193 are connected by means of a link 198 and pivot pins 199, 200.

The stud feed 135 and the spring feed 181 are apertured in order to permit operation of the stud carrier 37 and the spring carrier 38 therethrough, whereby the studs D and the spring S may be applied to the display cards C.

It will be noted that the operating slide 148 of the stud feed 135 is provided with an oblong aperture 201 (Fig. 18), so that it may reciprocate

without causing any interference with the stud carrier 37.

Fastener closing mechanism

The stud carrier 37 comprises a rod section 202 (Fig. 14) mounted in the end of a square reciprocating stud closing slide 203 and has a split resilient mandrel 204 projecting from its outer end which is adapted to fit resiliently within the projections of each stud D, whereby the studs D may be retained thereon and carried forwardly into engagement with the card C.

Similarly, the spring carrier 38 comprises a hollow rod section 205 mounted in the end of a square reciprocating spring closing slide 206. The hollow rod section 205 embraces an inner rod section 207 (Fig. 14) which projects outwardly of the end of the hollow rod section 205 in the form of a reduced split resilient hollow end 208, thereby forming a spring chuck 209 which is adapted to resiliently engage over the center projections of the springs S so as to carry them forward into engagement with the card C.

The stud closing slide 203 is guided in slots 210, 211, respectively, in the upper ends of the pedestals 14, 15, and the spring closing slide 206 is guided in slots 212, 213, respectively, in the upper ends of the pedestals 16, 17. The stud and spring closing slides 203, 204 are thus supported in horizontal aligned relation for sliding toward and away from each other and are retained in their respective slots by means of cap plates 214 and screws 215.

The closing slides 203, 204 and the stud and spring carriers 37, 38 thereon are operated from the main drive shaft 42 by means of cams 216, 217 secured on the shaft 42, and having cam pieces 218, 219 secured to their sides, whereby they are rendered double-acting (Figs. 1, 5, 7). Provision is made of a pair of bell-crank levers 220, 221, which are swingably mounted on blocks 222, 223, respectively, on the machine bed 10. The bell-crank levers 220, 221 are provided with cam followers 224, 225, respectively, which are adapted to engage with the cams 216, 217, and offset lower arms 226, 227 carrying cam followers 228, 229, which are adapted to engage with the cam pieces 218, 219.

The upper ends of the bell-crank levers 220, 221 are connected by means of universally pivoted lugs 230, 231, respectively, and links 232, 233 to one end of respective bell crank levers 234, 235 swingable on vertical studs 236, 237 which are supported on the rear portions of the left hand pedestal base 11 and the right hand pedestal base 12 by brackets 238, 239. The forward ends of the bell-crank levers 234, 235 are connected to the stud closing slide 203 and the spring closing slide 206 between the respective pedestals by means of screw studs 240, 241 (Fig. 8).

The stud and spring closing slides 203 and 206 are urged toward the center of the machine by coiled springs 242, 243 which are connected to the outer ends thereof by means of upstanding pins 244, 245 (Fig. 2) and secured at their inner ends upon stationary pins 246, 247 secured on the inner cap plates 214.

The spring closing slide 206 is provided with an outer extension 248 (Figs. 1 and 2) to which is secured a rearwardly-extending horizontal arm 249, which carries an adjustable screw 250, provided with a lock nut 251. The end of the screw 250 is adapted to abut the outer surface of the pedestal 17 in order to limit the closing

movement of the slide 206 and the spring carrier 38 thereon.

Thus, while the stud and spring carriers 37, 38 will be urged to closing position by the springs 242, 243, the precise location of the final closing operation will be determined by the contact of the adjustable stop screw 250 with the pedestal 17.

It will be noted that the cam pieces 218, 219 will engage the followers 228, 229 during a relatively short interval at the beginning of the closing movement of the carriers 37, 38 whereby said closing movement will be positively initiated. However, the final force of the fastener closing operation will be exerted solely by the closing slide springs 242, 243. The stud and spring carriers 37, 38 will be withdrawn by the action of the cams 216, 217 upon the followers 224, 225.

In connection with the closing operation, it will be noted from an observation of the cams 216, 217 in Figs. 5 and 7, that the followers 224, 225 will at first be permitted a small inward movement prior to the closing movement which is initiated by the cam pieces 218, 219, whereby the spring mandrel 204 and the spring chuck 209 (Figs. 8 and 14) will engage with the stud D and the spring S, respectively, while they are still held by the stud feed slide 141 and the spring feed slide 188 as shown in Fig. 18. The cams 216, 217 are shaped so that they will then provide a dwell, or even permit a slight reverse movement, whereby withdrawal of the feed slides 141, 188 will be permitted, after which the carriers 37, 38 will be fully advanced to closing position by the action of the cam pieces 218, 219, and the closing springs 242, 243.

Stripper mechanism

The stud and spring strippers 148 and 190b (Figs. 9 and 10) are swingably mounted on the mounting blocks 126, 128, respectively, by means of pins 252, indicated by a dotted line in Figs. 9 and 10, and are provided with semi-circular notches 253 in their lower edges which are adapted to embrace the upper surface of the stud and spring carriers 37, 38 when the strippers are in their lower position, as seen in Fig. 12, for example. The strippers 148, 190b are operated from the main drive shaft 42 by means of an arm 254 (Figs. 1 and 6) which is swingably mounted in a bracket 255 upon the machine bed 10, and carries a follower 256 engaged with a cam 257 on the shaft 42.

The strippers 148, 190b are connected for simultaneous operation by means of a stud 258 (Figs. 1 and 8) and a link 259 connects said stud 258 with the arm 254. A coiled spring 260 is provided which is connected between the stud 258 and an elongated projecting screw 261 (Fig. 1) carried by the spring magazine 117, whereby the follower 256 will be maintained in operative engagement with the periphery of the cam 257.

Operation

In operation, the stud magazine 116 will be filled with studs D, and the spring magazine 117 will be filled with springs S, and the operator will insert a display card C in the card holder 24 in such a position, determined by adjustment of the stop 31, that the perforations P of the card will be in alignment with the apertures 35, 36 of the card holder 24 and the clamping plate 32, as shown in Fig. 8.

The clutch rod 76 will then be tripped so as to

swing the clutch arm 68 downwardly about the pivot pin 70, (Figs. 1, 2, and 4) to pull it out of contact with the head 67 of the bolt 65, thus permitting the spring-urged bolt 65 to enter the slot 66 in the hub of the flywheel 59. Inasmuch as the bolt 65 is held in the inner aperture of the clutch body 63, the drive shaft 42 will be rotated by the constantly rotating fly wheel 59 as long as said bolt is engaged in the slot 66. The trip rod 76 will be maintained in its tripped position by virtue of the engagement of the rear end 98 of the clutch release lever 96 in the notch 99 of the trip rod 76 (Fig. 4).

This will cause the crank 50 to reciprocate the connecting rod 51 (Figs. 1 and 2) and the pawl 53 so that the ratchet wheel 39, the shaft 20 and the card holder 24 will be rotated in a step-by-step movement so as to bring each of the card perforations P successively into alignment with the stud carrier 37 and the spring carrier 38.

Each rotation of the main drive shaft 42 will also rotate the cam 153 so as to push the arm 155 forwardly against the force of the spring 157, the latter serving to return the arm 155 to its rearward position. This causes the arm 155 to oscillate so as to reciprocate the operating slide 149 by means of the link 159, and the stud feed slide 141 will also reciprocate because of its connection with the operating slide 149 by means of the screw 151 and the filler piece 152. Thus, during each step in the movement of the card holder 24, the stud feed slide 141 will reciprocate to bring a stud D from a position beneath the stud magazine 116 to a position in alignment with the stud carrier 37 (Figs. 7, 8 and 10). It will be understood that the stud escape mechanism 161 will operate to release one of the studs D at a time so that it will fall downwardly into position to be picked up by the stud feed slide 141. The stud escape mechanism 161 will be slid forwardly at each rearward movement of the stud feed slide 141, this being accomplished by the link 176 and the escape lever 177 which will be engaged by the roller 180 attached to the reciprocating link 159. The escape mechanism 161 will be returned to its rearward position by the spring 175.

The spring feed slide 188 (Figs. 6, 9 and 15) will be actuated from the main drive shaft 42 by the cam 191 (Fig. 1), the bell crank lever 193, and the link 198, so as to operate simultaneously with the operation of the stud feed slide 141 to bring a spring S from a position below the spring magazine 117 into a position in alignment with the spring carrier 38. At this time, the rotation of the cams 216, 217, will permit the followers 224, 225 on the bell crank levers 220, 221 to drop into the initial portions of the cam recesses, thus acting through the links 232, 233 and the bell crank levers 234, 235, to permit the springs 242, 243 to move the slides 203, 206 inwardly so as to advance the carriers 37, 38 toward the card simultaneously in opposite directions to engage the stud D and spring S, respectively, in the position shown in Fig. 18. The cams 216, 217 will then provide a slight dwell in the movement of the carriers 37, 38, as hereinbefore described, during which time stud and spring slides 141, 188 will be withdrawn by the action of the springs 157 and 195, respectively, so that the parts will occupy the positions shown in Figs. 21, 22. Continued rotation of the cams 216, 217 will permit a further drop of the followers 224, 225 into the cam recesses under the influence of the springs 242, 243, and will simultaneously bring the cam pieces 218, 219 into engagement with the followers

228, 229, thus operating, in conjunction with the springs 242, 243 to advance the carriers 37, 38 and close the stud and the spring upon the card C as shown in Fig. 12. However, it will be noted that the engagement of the cam pieces 218, 219, with the followers 228, 229, is of relatively short duration, so that said cam pieces will merely serve to positively initiate and accelerate the closing movement of the carriers 37, 38, which is completed solely by the springs 242, 243.

The engagement of the adjustable stop screw 250 with the pedestal 17 will limit inward movement of the spring carrier 38, and will determine the precise location in which the spring S and the stud D are finally closed, this location being at the plane of a card in the card holder 24 (Figs. 1 and 2).

As the closing movement occurs, the rotation of the cam 251 on the shaft 42 will permit the follower 256 (Figs. 1 and 6) to drop, thus permitting the spring 260 to act so that the strippers 148 and 190b will be swung downwardly so as to engage the carriers 37, 38, (Fig. 12) thereby insuring that neither the spring S nor the stud D will remain upon the carriers as they are withdrawn from the closing position.

The strippers 148 and 190b are provided because a situation may sometimes occur wherein either the stud carrier or the spring carrier will fail to pick up a spring or a stud, either because the supply in one of the magazines is exhausted, or for some other reason. It will be seen that if one of the snap fastener sections were applied to the card in the absence of the other snap fastener section, the first snap fastener section would not be retained upon the card, but would remain upon its carrier. This would result in jamming of the machine if the strippers 148 and 190b were not provided to remove the unassembled snap fastener section from the carrier, and thus provide a clear passage for the next spring or stud to be fed by the feed mechanism.

After a stud D and a spring S have been closed upon the card C, thereby forming an assembled snap fastener F, the carriers 37, 38 will be withdrawn by the action of the cams 216, 217 upon the followers 224, 225 in order to pick up the succeeding stud and spring, and the carrier 24 will be rotated another step in order to bring another perforation P into position to receive a stud and a spring, whereupon the preceding operations will be repeated.

The machine will continue to operate while the holder 24 is rotated, step-by-step, until all of the perforations P are supplied with snap fasteners, whereupon the clutch release pin 94 will raise the cam nose 95 (Figs. 1 and 4) in order to disengage the rear end 98 of the lever 96 from the clutch trip rod 76, thereby releasing the clutch arm 68 which will shift the bolt 65 and disengage the clutch 62. Releasing of the clutch arm 68 will also bring the lateral abutment 75 thereon into the path of the head 67 of the bolt 65 so that the drive shaft 42 will be brought to a positive stop. Simultaneously with raising of the cam nose 95, the cam projection 93 on the control disk 92 will engage the nose 115 of the bell-crank lever 105, thereby forcing the rear end of the bell-crank lever to the left as seen in Fig. 1, so as to shift to the right the annular groove 113 in the shaft 23 to which the clamping plate 32 is attached (Fig. 8), and thus release the clamping plate 32 from the card C. This operation will also engage the recess 108 with the detent 109, whereby the clamping plate 32 will be held in released posi-

tion so as to enable the card C to be removed and a fresh card inserted.

The clamping plate 32 will remain in this released position until the machine is again started by depressing the clutch trip rod 76, whereupon the cam piece 101 will strike the follower 102 and thereby move the bell crank lever 103 to disengage the detent 109 from the recess 108. This will permit the spring 114 to move and hold the clamping plate 32 in engagement with the card C.

One advantage of the improved carding machine herein disclosed is that it will rapidly and economically perform an operation which has heretofore been slow and expensive.

Another advantage is that the machine will require no attention on the part of the operator excepting to insert the fresh cards, trip the clutch, and remove the filled cards. After a fresh card has been inserted in the holder 24, it will merely be necessary for the operator to trip the clutch, whereupon the machine will operate automatically to apply the proper number of snap fasteners to the card, and then stop.

The operation of the machine is rapid, and it will be noted that the steps of inserting and removing the cards may be expedited by inserting a fresh card behind the filled card and then removing the filled card, so that the cards may be changed with a single motion of the operator's hand.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a machine for applying snap fasteners to cards, a card holder, means for closing a snap fastener upon a card in said card holder including a stud carrier and a spring carrier supported at opposite sides of said card holder, said carriers comprising means for supporting a stud and a spring, respectively, devices for feeding successive studs and springs to said stud carrier and said spring carrier, respectively, mechanism for moving said card holder rotatively to bring different radially disposed portions of the card successively into position between said stud carrier and said spring carrier, and means for continually operating said closing means, said feeding devices, and said card holder moving mechanism in periodic timed relation, whereby a circular series of snap fasteners will be applied to the card.

2. The invention as defined in claim 1, in which said operating means includes a device for automatically stopping the machine after the completion of the application of the circular series of snap fasteners to the card, and a device for manually restoring said machine to operation.

3. The invention as defined in claim 1, in which said fastener closing means includes a pair of closing slides supporting said stud carrier and said spring carrier for closing and opening movement, a pair of operating springs providing a closing force upon said slides, and an adjustable stop for limiting the closing movement of one

of said slides, whereby the fastener springs and studs will be closed at a predetermined location in the machine.

4. The invention as defined in claim 1, including a pair of strippers, and means for moving said strippers into engagement with said stud carrier and said spring carrier behind said stud and said spring, respectively, at the end of each closing operation thereof, said carriers being withdrawn away from the card and past said strippers after each closing operation, whereby accidental adherence of the studs and the springs to the carriers will be prevented.

5. The invention as defined in claim 1, including a plate adapted to clamp a card in said card holder, mechanism resiliently urging said plate to clamp said card, and means for withdrawing said plate from said card after a predetermined number of closing operations by said fastener closing means, whereby the card in said card holder may be replaced by another card.

6. The invention as defined in claim 1, in which said stud and spring feeding devices include a stud magazine and a spring magazine supported in positions offset from said stud carrier and said spring carrier, respectively, a stud slide for transferring the studs from said stud magazine to said stud carrier, and a spring slide for transferring the springs from said spring magazine to said spring carrier.

7. In a machine for applying snap fasteners to cards, an elongated, horizontally disposed stud supporting carrier and an elongated, horizontally disposed spring supporting carrier aligned therewith, means for reciprocating said carriers longitudinally to close a stud and a spring on a card in a predetermined vertical plane in right-angular relationship to the axes of said carriers, a holder for supporting a card in a predetermined lateral location between said carriers in said plane, and means to apply the stud and the spring resiliently to said stud supporting carrier and said spring supporting carrier respectively prior to the closure on said card of the stud and the spring.

8. The invention as defined in claim 7, including devices for feeding successive studs and springs to said stud carrier and said spring carrier, respectively, and means for imparting step-by-step rotation to said card holder, whereby a circular series of snap fasteners will be applied to said card.

9. The invention as defined in claim 8, including means for operating said carrier reciprocating means, said feeding devices, and said card holder rotating means in timed relation, and a device for automatically stopping said operating means when said card holder has made one complete revolution.

10. The invention as defined in claim 9, including a plate for clamping said card in said card holder, and a device for withdrawing said plate from the card when the card holder has made one complete revolution.

11. In a machine for applying snap fasteners to cards, a pair of aligned carriers comprising resilient means for frictionally holding complementary fastener sections, a holder for supporting a card in a predetermined transverse plane between said carriers, means for simultaneously reciprocating said carriers toward and away from each other a predetermined number of times to close fastener sections carried thereon upon a card in said holder, a stripper normally out of operative engagement with one

15

of said carriers, and means for holding said stripper in engagement with said last-mentioned carrier during withdrawal thereof past said stripper, whereby accidental adherence of fastener sections thereon will be prevented.

12. In a machine for applying snap fasteners to cards; a card holder having a flat base, a pair of parallel side guides, and an end guide; and a plate adapted to clamp a card against said flat base between said guides, said card holder and said plate being centrally secured upon the adjacent ends of a pair of aligned shafts and being formed with aligned pairs of apertures equidistant from the axes of said shafts, whereby springs and studs may be applied to opposite faces of the card.

13. In a machine for applying snap fasteners to cards, a horizontally disposed, slidably mounted, elongated stud carrier, a horizontally disposed, slidably mounted, elongated spring carrier, and means for simultaneously reciprocating said carriers horizontally toward each other a predetermined number of times for closing springs and studs carried thereby, said stud carrier comprising an annular end surface and a fixed resilient mandrel extending outwardly of said surface and adapted to enter the back of a stud to frictionally hold the same prior to its closure on a spring.

14. In a machine for applying snap fasteners to cards, a horizontally disposed, slidably mounted, elongated stud carrier, a horizontally disposed, slidably mounted, elongated spring carrier, and means for simultaneously reciprocating said carriers horizontally toward each other a predetermined number of times for closing springs and studs carried thereby, said spring carrier comprising an annular end portion and a fixed resilient chuck secured centrally in said end portion and adapted to embrace a portion

16

of a spring to frictionally hold the same prior to its closure on a stud.

15. In a machine for applying snap fasteners to cards, a stud feed comprising a bar having a horizontal stud channel, an entrance channel intersecting said stud channel from above, and a stud feed slide in said stud channel, said slide having a notched end portion of reduced thickness for engaging the central projection of a stud, and said slide further having an upper edge portion of reduced thickness rearward of and communicating with said notched end portion for supporting a stud; and means for reciprocating said feed slide in said stud channel whereby a stud in said entrance channel and supported upon the upper edge portion of said slide will drop into the stud channel, and said notched end will feed said stud along the stud channel.

Certificate of Correction

Patent No. 2,575,019

November 13, 1951

MAX KIESSLING

It is hereby certified that error appears in the printed specification of the above numbered patent requiring correction as follows:

• Column 14, line 11, for "stripers" read *stripers*; line 19, for "perations" read *operations*;

and that the said Letters Patent should be read as corrected above, so that the same may conform to the record of the case in the Patent Office.

Signed and sealed this 26th day of February, A. D. 1952.

[SEAL]

THOMAS F. MURPHY,
Assistant Commissioner of Patents.
